SHINGLE

Ernest C. Matthews and Loraine M. Clary,
Eureka, Calif., assignors to The Paraffine Com-
panies, Inc., San Francisco, Calif., a corpora-
tion of Delaware

Application April 20, 1932, Serial No. 606,376

3 Claims. (Cl. 108—7)

Our invention relates to a shingle, and particularly to an interlocking shingle.

It is among the objects of our invention to provide a shingle adapted for engagement with an 5 adjacently laid shingle to form a double interlock.

Another object of our invention is to provide shingles having interlocking means of the character described which restrains the shingles against relative movement in three directions, as 10 compared with the ordinary interlock which is capable of restraining the shingles against relative movement in only two directions.

Still another object of our invention is to provide an interlocking means of the character described which is as easily formed and as readily 15 engaged as the ordinary interlocking means.

A further object of our invention is to provide improved means for aligning the shingles in the nailing position, so that the shingles may be laid 20 on a roof more accurately and at the same time more rapidly.

Our invention possesses other objects and features of advantage, some of which, with the foregoing, will be set forth in the following description 25 of our invention. It is to be understood that we do not limit ourselves to this disclosure of species of our invention, as we may adopt variant embodiments thereof within the scope of the claims.

30 Referring to the drawings:

Figure 1 is a plan view of a shingle embodying our invention; and

Figure 2 is a similar view showing a variant form of shingle.

35 Figure 3 is a detail view showing the engaged locking means of two interlocked shingles; portions of the shingles being broken away to illustrate the interlock more clearly.

Figure 4 is a plan view showing a plurality of 40 the shingles in the laid position.

Figure 5 is a plan view showing the shingles in the cutting position.

Figure 6 is a detail view similar to that shown 45 in Figure 3, but illustrating a variant form of interlock.

In terms of broad inclusion, the interlocking shingle embodying our invention comprises a sheet having a receiving slot at one corner and a locking tab at an adjacent corner adapted to engage with the slot of an adjacently laid shingle. A slit is also provided adjacent the tab for further engagement with the portions of the adjacently laid shingle near the receiving slot. This forms a double interlock which restrains the interlocked shingles against relative movement in

three directions. Improved means are also provided for aligning the shingle in the nailing position, so that a workman is enabled to lay the shingles more accurately and in less time.

In greater detail, the interlocking shingle embodying our invention comprises a sheet 2 of any suitable shape. The sheet shown in Figure 1 is of generally rhombic shape having straight sides. In a modified form of shingle, as shown in Figure 2, the sheet is of the same general shape as shown 10 in Figure 1, but is provided with curved sides. These shingle shapes are shown merely for purposes of illustration; it being understood that other shapes may be used.

The interlocking means of our invention comprises a receiving slot 3 at one corner of the shingle and a locking tab 4 at an adjacent corner adapted to engage with the slot of an adjacently laid shingle. The receiving slot 3 is preferably positioned to extend inwardly from the bottom 15 edge 5 of the shingle, and is preferably provided with an enlarged portion 6 to facilitate engagement with the locking tab. The locking tab 4 is preferably provided with an extended portion 7 projecting outwardly from the side edge 8 of the 20 shingle; this portion being taken from the corner of an adjacently cut shingle near its receiving slot. Note Figure 5 which shows a plurality of the shingles in their cutting position.

The remaining portions of the tab 4 are preferably formed by a slit 9 extending inwardly from the shingle edge 8 and a second slot 11 intersecting the slot 9 and extending at an angle thereto. The slot 9 is preferably cut to extend substantially horizontal and the intersecting slot 11 is preferably cut to extend substantially vertical, the latter slot preferably extending downwardly from the inner end of the first slot. The preferred method of laying the shingles on a roof is shown in Figure 4; the shingles being laid in overlapping 35 courses, with the shingles in a course overlapped and interlocked, and with the shingles in each course staggered with respect to shingles of an adjacent course.

The details of the interlock are best shown in 45 Figure 3. Here it is seen that the tab 4 of one shingle engages the receiving slot 3 of an adjacently laid shingle, and that the slit 11 engages the portions of the adjacently laid shingle above the receiving slot 3. This forms a double interlock and restrains the shingles against relative movement in three directions; viz., against lateral relative movement in both directions and against vertical relative movement in one direction. This 50 is a material improvement over the ordinary tab 55

and slot interlocks, because the latter restrain the shingles against relative movement in two directions only; viz., against lateral relative movement in one direction and against vertical relative movement in one direction. The double interlock of our invention is as simply engaged as the ordinary interlocking means, and not only provides a more secure and permanent fastening, but also serves to more firmly hold the shingles against movement when they are being shifted into alignment and nailed.

As best shown in Figure 4, a nail 12 is driven through the corner of the shingle adjacent the receiving slot 3, and a second nail 13 is driven through the opposite corner. In order to facilitate laying the shingles, means are provided for aligning the shingles in position, and in order to save time and avoid unnecessary movements on the part of a workman the aligning means is positioned adjacent the point where the first nail is driven. A suitable marker, such as the notch 14, is formed on the side edge of the shingle adjacent the receiving slot 3. This notch is positioned to register with the upper edge of the underlying shingle when the shingle being laid is in the proper position.

Thus, when a shingle is being laid it is first slipped into interlocking engagement with the previously laid shingle, and then the shingle is shifted until the notch 14 is in the proper position. At this time the workman's eyes and at least one hand is in the region about the corner of the shingle having the receiving slot, and, since the nail 12 is driven first, unnecessary movements back to this position when the nail is driven are eliminated. Workmen are accustomed to driving the nail 12 first when laying interlocking shingles, because it gives them an opportunity to keep the bottom edge of the shingle they are nailing in line with the bottom edges of others in the same course. The second nail 13 is then driven.

Another important feature of the above described aligning means is that the marker is positioned substantially the maximum distance possible away from the interlocking corner about which the shingle pivots when it is being shifted into alignment. This arrangement reduces errors

in alignment and results in a more accurately positioned shingle. A second notch 16 is also preferably provided along the edge of the shingle and spaced from the notch 14. If this second notch is used for alignment a greater degree of overlap is secured.

Figure 6 shows a variant form of the interlocking means embodying our invention. In this construction the tab 17 projects outwardly from the side edge 18 and lies wholly without the body 10 of the shingle; the tab being cut entirely from the corner of an adjacently cut shingle near its receiving slot 19. In this construction a slit 21 is provided extending downwardly as a continuation of the edge 18 and separating 15 a portion of the tab from the body of the shingle for engaging portions of the adjacently laid shingle over the receiving slot.

We claim:

1. A shingle comprising a sheet having a sloping 20 side edge, a receiving slot at one corner of the sheet and extending from the bottom edge of the shingle, a locking tab at an adjacent corner projecting outwardly from the sloping side of the shingle to provide a substantially V-shaped notch 25 between the tab and side edge, and a slot extending into the body of the shingle from the base of said notch.

2. A shingle comprising a sheet having a sloping 30 side edge, a receiving slot at one corner of the sheet and extending from the bottom edge of the shingle, a locking tab at an adjacent corner projecting outwardly from the sloping side of the shingle and having a sloping upper edge to provide a substantially V-shaped notch between the 35 tab and side edge, and a slot extending into the body of the shingle from the base of said notch.

3. A shingle comprising a substantially rhombic 40 shaped sheet, a receiving slot at one corner of the sheet and extending from the bottom edge of the shingle, a locking tab at an adjacent corner projecting outwardly from the sloping side of the shingle to provide a substantially V-shaped notch between the tab and side edge, and a slot 45 extending into the body of the shingle from the base of said notch.

ERNEST C. MATTHEWS.
LORAINE M. CLARY.
